UNITED STATES PATENT OFFICE.

ALLEN MORELL, OF CRIPPLECREEK, COLORADO.

KEY-GUARD.

SPECIFICATION forming part of Letters Patent No. 763,920, dated June 28, 1904.

Application filed September 12, 1903. Serial No. 172,991. (No model.)

To all whom it may concern:

Be it known that I, ALLEN MORELL, a citizen of the United States, residing at Cripple-creek, in the county of Teller and State of 5 Colorado, have invented a new and useful Key-Guard, of which the following is a specification.

This invention is an improved construction of key-guard, the object being to provide a 10 simple and efficient device which can be attached to the inner face of the door and by means of which the key of the lock can be rigidly fastened, thereby preventing any one from the outer side of the door turning the 15 key or picking the lock; and with this object in view the invention consists, essentially, of a slotted bracket-arm, to which is pivoted a plate or bar folded centrally upon itself providing a keeper for receiving the ring of the 20 key, the said keeper portion being slotted longitudinally and having a spring-actuated lever pivoted upon the upper side thereof, said lever carrying a finger adapted to be projected through the slots of the keeper and 25 also through the ring of the key, thereby locking the said key within the keeper.

The invention consists also in certain details of construction hereinafter fully described, and pointed out in the claims.

30 In the drawings forming part of this specification, Figure 1 is a perspective view showing the practical application of my invention. Fig. 2 is a detail perspective view of the guard detached from the door. Fig. 3 is a longitudinal sectional view of the keeper and lever. Fig. 4 is a view of the blank from which the 35 keeper is formed. Fig. 5 is a detail perspective view of the lever and finger connected thereto.

40 In carrying out my invention I employ a horizontal bracket-arm A, having a foot-piece A', by means of which it is securely fastened to the door-frame or door, said arm being slotted longitudinally, as shown at A², and 45 pivotally connected to this arm is the keeper B, formed from a single piece of metal bent centrally upon itself, as shown at B', the pivot B² connecting the ends of the same, said pivot working in the longitudinal slot A², so that

the keeper has not only a pivotal movement 50 upon the arm, but also a movement back and forth or toward or away from the face of the door, so that the guard can be made to accommodate keys with different lengths of shanks. A rivet B³ connects the members adjacent the 55 pivot-point, and at B⁴ the members are spread slightly, so as to make the outer or free end of the keeper sufficiently large to receive all varieties of keys. The keeper is slotted longitudinally, as shown at B⁵, both top and bottom, and is provided with integral pivot-ears B⁶ and the upwardly-extending post B⁷. An elbow-lever C, having trunnions C', is pivoted between the ears B⁶, said lever carrying a finger C², which is adapted to be projected 60 through the slots B⁵ and also through the ring of the key, which is inserted in the keeper, and the upper end of the lever is formed with a downwardly-extending stud C³, and between the post B⁷ and stud C³ is the spring D, the 65 purpose of which is to hold the finger C² in the slots B⁵ and ring of the key.

In operation the ring of the key is turned to a horizontal position after the door has been locked, and the keeper is then swung 75 upon the bracket-arm and the ring of the key inserted therein, the lever being raised, as shown in Fig. 2, and after the ring of the key has been inserted to the proper point the lever is released, and the spring will force the 80 finger C² downwardly through the slots, thereby locking the said key in the keeper, as most clearly shown in Figs. 1 and 3, thereby preventing the key being turned and also preventing it being pushed from the lock. 85

It will thus be seen that I provide a simple key-guard by means of which the interference with the key from the outer side of the door is prevented.

Having thus fully described my invention, 90 what I claim as new, and desire to secure by Letters Patent, is—

1. A key-guard comprising a bracket-arm having a longitudinal slot, a keeper pivotally connected to said bracket-arm, the pivot being adapted to slide in a horizontal slot in said bracket-arm, the free end of said keeper being slotted longitudinally, and the spring-ac-

tuated lever having a finger adapted to be projected through the slots of the keeper, as set forth.

2. A key-guard comprising a longitudinally-slotted bracket-arm, the keeper formed from a strip of metal bent centrally upon itself, pivotally connected to the bracket-arm, slotted longitudinally both top and bottom, provided with pivot-ears and the upwardly-ex-

tending post, the lever pivoted between the ears and carrying a downwardly-extending finger, and also a downwardly-extending stud, and the spring arranged between the stud and post, for the purpose specified.

ALLEN MORELL.
